UNITED STATES PATENT OFFICE

THOMAS E. MURRAY, JR., OF BROOKLYN, NEW YORK, ASSIGNOR TO METROPOLITAN ENGINEERING COMPANY, A CORPORATION OF NEW YORK

CAR JOURNAL BOX

Application filed June 4, 1924. Serial No. 717,728.

My invention aims to provide certain improvements in journal boxes for railway cars to permit a reduction in weight and in the cost of manufacture.

5 The accompanying drawings illustrate an embodiment of the invention.

Fig. 1 is a half plan and half horizontal section of the cellar of a journal box;

10 Fig. 2 is a vertical longitudinal section of the same;

Fig. 3 is a transverse vertical section of the same on the line 3—3 of Fig. 1;

Fig. 4 is a similar section on the line 4—4 of Fig. 1, showing only the upper part.

15 Figs. 5 and 6 are similar views of a modified detail.

Referring to the embodiment of the invention illustrated, the showing is directed to the cellar only of the box. The cellar is made 20 in two segments welded together. One segment is made of cast steel or similar metal and forms the top 1 with projecting portions 2 which constitute an arch bar seat with lateral flanges 3 in which are located bolt 25 openings 4; this segment including also downward flanges 5 which constitute inside stop pieces with vertical grooves 6 in their outer faces.

The lower segment is stamped out of sheet 30 metal and constitutes the bottom 7 and sides 8 of the cellar. The sides are bent in to form vertical grooves 9 which register and lock into the grooves 6 in the inside stop pieces, and which are in line also with the bolt 35 openings 4 in the flanges of the top segment.

The top 1 is preferably formed with side flanges 10 (Fig. 4) which come down to the upper edges of the sides 8 of the lower segment and are welded thereto. Any one of 40 various welding methods may be used; for example the parts may be pressed together while an electric current of extremely high density is passed across the joint for a very brief regulated period of time. The take-up or advance of the parts toward each other is such as to extrude a certain quantity of metal laterally. In order to make a neat joint, the top segment is arranged to overlap the outside of the joint. In Fig. 4 the 45 flange 10 is shown rabbeted on its inner side

so as to bring the inner face thereof flush with the inner face of the lower segment 8; and a flange 11 is brought down on the outside of the segment 8 so as to provide a good lateral brace.

In the alternative constructions shown in Figs. 5 and 6, the flange 10 of the upper segment is grooved so as to bring the edges down on both sides of the lower segment 8. In Fig. 6, in addition, there is a raised rib 12 along the center of the groove in the edge of the flange 10; which rib concentrates the area through which the current passes and thus facilitates the making of the weld.

Though I have described with great particularity of detail certain embodiments of my invention, yet it is not to be understood therefrom that the invention is restricted to the particular embodiments described. Various modifications may be made by those skilled in the art without departure from the invention as defined in the following claim.

What I claim is:

A journal box cellar comprising a cast upper segment comprising a top portion constituting an arch bar seat with bolt openings and projections constituting inside stop pieces, and a sheet metal lower segment having grooves at the sides registering with said stop pieces and in line with said bolt openings, the cast upper segment having flanges on its lower face abutting against the edges of the sheet metal lower segment and having flanges beyond said stop pieces projecting down on the outside of the lower segment, 85 said segments being welded together along the abutting edges of the flanges and the lower segment.

In witness whereof, I have hereunto signed my name.

THOMAS E. MURRAY, JR.
